UNITED STATES PATENT OFFICE

2,547,556

PUNCTURING AND DISPENSING DEVICE
FOR OIL CANS

James E. Benigar, Tulsa, Okla.

Substituted for application Serial No. 349,075,
August 1, 1940. This application May 28, 1947,
Serial No. 751,099

3 Claims. (Cl. 222—83)

1

This application is a substitute for application Serial Number 349,075, filed August 1, 1940.

This invention relates to a novel device for opening and dispensing the contents of cans and more particularly to a device adapted for use for opening sealed cans of oil and for dispensing the contents thereof into the crankcase of a motor vehicle.

More particularly, it is an aim of the invention to provide a device including an arcuately shaped frame having means for detachably and slidably mounting a can therein and a handle for supporting said frame, said handle being compressible for actuating means for piercing the ends of the can to form a dispensing opening in one end thereof and a vent opening in the opposite end of the can.

Still another object of the invention is to provide a device having a fixed cutting member and a movable cutting member for piercing the opposite ends of a can, said movable cutting member being so constructed that when moved to a projected position it will first move the can relatively to the fixed cutter to cause the fixed cutter to penetrate one end of the can and thereafter swing to a position for penetrating the opposite end of the can.

Still a further aim of the invention is to provide a device of simple construction which may be economically manufactured and sold and which will be light and durable.

Other objects and advantages of the invention will hereinafter become more fully apparent from the following description of the drawing, which illustrates a preferred embodiment thereof, and wherein—

Figure 1 is a side elevational view of the opener and dispenser with the movable parts thereof shown in retracted positions.

Figure 2 is a longitudinal vertical central sectional view of the same with the movable parts thereof shown in projected positions.

Figure 3 is a transverse sectional view taken substantially along the plane of the line 3—3 of Figure 2, and

Figure 4 is a similar view taken substantially along the plane of the line 4—4 of Figure 2.

Referring more particularly to the drawing, wherein like reference characters designated like or corresponding parts throughout the different views, 10 designates generally the can opening and dispensing device comprising the invention, and which includes a frame, designated generally 11, comprising a bar 12 and an elongated plate 13 which is secured in any suitable manner, not shown, to one side of the bar 12. One end of the bar 12 extends beyond the corresponding end of the plate 13 and the opposite end of the plate 13 extends beyond the opposite end of the bar 12. Plate 13, as best seen in Figures 3 and 4, is arcuately shaped in cross section and secured on

2

its outer side to the bar 12. Plate 13 is shaped to receive a portion of a can, shown in dotted lines at 14, and the frame 11 is also provided with an arcuately shaped spring clip 15, which is secured intermediate of its ends to the outer or exposed side of the bar 12 and which is disposed transversely of the longitudinal axis of the frame 11. The ends of the spring clip 15 are adapted to engage and yieldably retain the can 14 in position in the frame 11, as illustrated in Figures 1 and 2. The extended, upper end of the bar 12 is bent to project at an oblique angle to the opposite end of the bar 12 and away from the plate 13 to form a handle portion 16 which is provided with an opening 17, adjacent its free end and by means of which the device 10 may be hung on a hook or other supporting means, not shown. The bar 12 adjacent the end thereof which forms the handle portion 16 is provided with an elongated longitudinal opening 18 the lower portion of which registers with a longitudinal slot 19 in the upper end of the plate 13. Bar 12 is provided with spaced outwardly projecting web or flange portions 20 which are suitably secured to the outer side thereof and contiguous with the slotted opening 18 which is disposed to communicate with the space between the flange or web portions 20, as best seen in Figure 3.

A cutter 21 has a shank portion the free end 22 of which is disposed longitudinally of the plate 13, adjacent its lower end, and intermediate of its side edges, and which is secured to the plate 13 and the lower end of the bar 12 by fastenings 22'. The shank portion of the cutter 21, adjacent its secured end 22, is bent to project outwardly of the plate 13 to form the shank portion 23 which terminates at its outer end in a cutting blade 24 which projects upwardly therefrom. The side edges 25 of the blade 24 are sharpened to form cutting edges and the upper, free end of the blade 24 is bent to extend inwardly and upwardly relatively to the frame 11 and is tapered to terminate in the upwardly projecting piercing point 26. Blade 24, as best seen in Figure 4, is substantially wider than the portions 22 and 23 which form the shank of the cutter 21.

A blade 27 is loosely mounted, intermediate 50 of its ends, on a bolt 28 which extends through the flanges 20 and which is provided with an attaching nut on its threaded, shank end. One end 29 of the blade 27 extends through the slot 18 and is normally disposed above the upper end of the can 14. A handle portion 30, which is arcuately shaped in cross section, is provided with ears 31 at one end thereof which are disposed on the outer side of the flange portions 20 which are apertured to loosely engage the bolt 28 for pivotally mounting the handle portion 30 beneath the handle portion 16 with its inner

side facing upwardly. The opposite, shank end 32 of the blade 27 extends into the upper, inner side of the handle portion 30. A spring 33 is coiled intermediate of its ends around the bolt 28. One end 34 of the spring 33 engages beneath the handle portion 16 and the opposite end 35 of the spring is attached to the shank end 32 for urging said end and the handle portion 30 downwardly and away from the handle portion 16. The end 29 of the blade 27 is provided with an unsharpened under edge portion 36 which rests on the upper end of the can 14 when the blade 27 is in a retracted position, as seen in Figure 1, and is provided at its outer end with a sharpened blade portion 37.

From the foregoing it will be seen that the spring 33 normally holds the blade 27 and handle portion 30 in the positions, as seen in Figure 1, so that a can 14, containing oil or the like, may be inserted into the frame 11 and yieldably held in the position, as seen in Figure 1, by the spring clip 15 with a portion of one end of the can resting on the point 26 and with the unsharpened portion 36 of the blade 27 engaging against the opposite end of the can. The lower, extended end of the plate 13 forms a spout 38 which is adapted to be inserted in the filling neck, not shown, of the crankcase of the motor vehicle. The opening and dispensing device 10 is held by the handle portions 16 and 30 and after the spout 38 has been inserted in a crankcase filling neck the portions 16 and 30 are compressed relatively to one another to cause the handle portion 30 to swing upwardly toward the handle portion 16. This upward movement of the handle portion 30 will rock the blade 27 to cause its shank end 32 to move upwardly and its blade end 29 to move downwardly. The downward movement of the end 29 will cause the portion 36 to press against the upper end of the can 14 to slide the can downwardly relatively to the frame 11 so that the lower end of the can will be pierced by the point 26 and cut by the edges 25 to form an opening therein. The shape of the blade 24 will cause the portion cut thereby to be rolled inwardly of the can and away from the opening, seen in Figure 4. The upper end of the shank portion 22 will form a stop for limiting the downward movement of the can 14. The rocking movement of the blade end 29 will bring the blade portion 37 into engagement with the upper end of the can 14 when the can has reached the position, as seen in Figure 2, so that further downward movement of end 29 will cause the blade portion 37 to pierce the upper end of the can 14 to form a vent opening in the upper end thereof to permit the oil to flow freely from the opening formed by the blade 24 into the spout 38 and therealong to crankcase neck. When pressure on the handle portion 30 is released the spring 33 will cause the handle portion 30 and blade 27 to return to their positions, as seen in Figure 1, so that after the contents of the can 14 have been dispensed it may be readily removed by an upward and outward pull thereon and the device 10 is then ready to receive another can to be opened and dispensed.

Various modifications and changes are contemplated and may obviously be resorted to as only a preferred embodiment of the invention has been disclosed.

I claim as my invention:

1. An opening and dispensing device for cans comprising a frame, said frame being arcuately shaped in cross section for engaging a portion

only of the side wall of the can and being provided with spring means for slidably and detachably connecting a can thereto, fixed piercing means for engaging one end of the can, movable cutting means for engaging the opposite end of the can, and compressible handle means for supporting the device and for actuating said movable cutting means, said movable cutting means having a cutting edge at one end thereof and being constructed and arranged whereby an unsharpened longitudinal edge thereof will initially engage the can for moving the can relatively to the frame to cause the piercing means to pierce one end of the can and said cutting edge to thereafter pierce the opposite end thereof to form dispensing and vent openings, respectively, therein.

2. An opening and dispensing device for cans comprising an elongated frame, said frame being arcuately shaped in cross section, one end of said frame forming a holder adapted to receive a can and to engage a portion of the side wall thereof, a spring connected, intermediate of its ends, to said end and adapted to engage and slidably hold the can in engagement with the holder, the other end of the frame forming a pouring channel, a cutting member fixedly secured in the channel and adapted to engage an end of the can, a handle having a shank secured to the outer side of the frame, said handle being disposed beyond the holder and providing means adapted to be grasped for supporting the device, and a cutting blade pivotally mounted, intermediate of its ends, on the handle and having one end adapted to engage the opposite end of the can, said end of the cutting blade having a blunt portion for initially engaging and moving the can so that the first mentioned end thereof will be pierced by the cutting member, when the cutting blade is actuated, and a sharpened portion for thereafter engaging and piercing the other end of the can, said device being held, when the can is opened, so that the contents of the can will flow into the pouring channel.

3. An opening and dispensing device for cans comprising an elongated frame, means for detachably mounting a can in the frame for longitudinal sliding movement relatively thereto, fixed piercing means secured to the frame and engaging one end of the can, and a manually actuated lever pivotally mounted on the frame having an unsharpened edge disposed to initially engage the opposite end of the can for moving the can in the frame to cause the piercing means to initially pierce the first mentioned can end when the lever is swung in one direction, said lever having a sharpened end disposed to thereafter engage and pierce the last mentioned can end.
